UNITED STATES PATENT OFFICE

155,328

DESIGN FOR A DISPLAY SIGN

Robert F. Baker, Norwood, Ohio, assignor to
 Robert F. Baker, Chris Katsetos, Fred Weiland, R. Frankel, and G. Frankel, doing business as Ohio Advertising Display Company

Application December 20, 1946, Serial No. 135,629

Term of patent 3½ years

(Cl. D1—12)

To all whom it may concern:

Be it known that I, Robert F. Baker, a citizen of the United States, residing at Norwood, in the county of Hamilton and State of Ohio, have invented a new, original, and ornamental Design for a Display Sign, of which the following is a specification, reference being had to the accompanying drawing, forming a part thereof.

Figure 1 is a perspective view of a display sign showing my new design;

Figure 2 is a perspective view showing the side opposite that shown in Figure 1;

Figure 3 is a fragmentary perspective view of a portion of the left end of the sign as shown in Figure 2; and

Figure 4 is a fragmentary perspective view showing the details of the side panels thereof.

The dominant feature of the design is the portion shown in full lines.

I claim:

The ornamental design for a display sign, substantially as shown and described.

ROBERT F. BAKER.
